FIG. 1

FIG. 2

INVENTOR
Paul Egnatoff
BY
Arlam S. Schatz
ATTORNEY

UNITED STATES PATENT OFFICE.

PAUL EGNATOFF, OF SASKATOON, SASKATCHEWAN, CANADA.

SUGAR-DISPENSER.

1,361,146.

Specification of Letters Patent.

Patented Dec. 7, 1920.

Application filed May 21, 1919. Serial No. 298,598.

To all whom it may concern:

Be it known that I, PAUL EGNATOFF, a citizen of Russia, residing at Saskatoon, Province of Saskatchewan, and Dominion of Canada, have invented certain new and useful Improvements in Sugar-Dispensers, of which the following is a specification.

This invention relates to improvements in apparatus for dispensing sugar, particularly adapted for the use of hotels, restaurants and the like eating places.

The principal object of the invention is to provide an apparatus in which uniform quantities of sugar may be dispensed directly into a cup containing a beverage, without the use of a spoon.

A further object is to provide a dispensing device having a tight fitting cover so as to prevent contamination of the sugar contained therein, by the entrance of a spoon, and also preventing flies and like insects, as well as dust from entering the interior.

A still further object is to provide means whereby an exact uniform quantity of sugar is delivered at each operation of the device in an easy and convenient manner.

These and other like objects are attained by the novel construction and combination of parts hereinafter described, and shown in the accompanying drawings, forming a material part of this disclosure, and in which—

Figure 1 is a side elevational view showing a sugar container made in accordance with the invention, parts being broken away in order to disclose the interior construction, and

Fig. 2 is a bottom plan view of the same.

Referring to the drawings, a hollow bell-shaped base is indicated by the numeral 10, the same having a beaded edge 11 adapted to be placed upon any relatively level surface as a table. The narrow portion 12 of the base element is formed with a bowl shaped container 14, having screw threads 15 formed upon its upper edge adapted to receive the cover plate 16, in an obvious manner, it being understood that the cover plate 16 may be readily removed when it is desired to refill the contents of the container.

The bottom or inner wall 18 of the container is provided with a single circular opening 19 through which sugar may pass, this opening being alinable with another opening 20, formed in the upper element 21,

of a fork shaped structure, joined by a narrow curved element 22, with the lower fork 23, these forks passing into the hollow base 10 through openings appropriately formed therethrough.

Another opening 24 passes through the lower element 23, of the fork section and which may be drawn outwardly so as to register with an opening 25 in the bottom 65 of the measuring chamber 26, which is supported immediately below in the center of the opening 19, in the sugar bowl base, by pairs of laterally extending arms 27 secured to the inner sides of the reduced portion 12. 70

This fork is normally held in a forward position due to the pull of a coiled tension spring 29, one end of which is attached to the lower fork element 23 near its outer end, 75 while the other end of the spring is secured to the inner surface of the base element 10 in any appropriate manner.

A handle 30 is secured to the outer surface of the main container 14 by which the apparatus may be readily maneuvered and pivotally engaged to it by the pin 31 is a lever 32, having a bent arm 33, formed with an eye 34, engaging with the arcuate connecting elements 22 of the forks, the bent 85 portion 35 of the lever 32 being receptive of the finger of an operator so that the same may be drawn back, causing a retraction of the fork elements 21 and 23 so that the opening 20 normally registering with the opening 19, is moved outwardly, the upper surface of the solid fork 21 preventing the passage of sugar from the main container, while the measuring chamber 26, being in a fixed position, permits the opening 25 to 90 be alined with the opening 24 in the lower fork element 23, thereby allowing its contents to drop out, the contents being normally held within the chamber by the fork element 23 which acts as a cover to the 100 opening.

From the foregoing it will be seen that a neat appearing and convenient article for table use has been disclosed, in which the sugar or other material held in the container is prevented from contamination, and that the device will dispense a certain definite amount of the sugar at each time the lever 32 is retracted, the same being normally drawn into a closed position by the 110 action of the spring 29.

Having thus described my invention what

I claim as new and desire to secure by Letters Patent, is—

In a sugar dispenser, the combination with a bowl, a hollow base extending therebelow, and an imperforate cover removably engaged with the top of said bowl, said bowl having an opening in its lower wall, a measuring chamber secured in said base immediately below the mentioned opening, 5 said measuring chamber having an opening in its lower portion in alinement with the opening in said container, a pair of fork bars rigidly joined together, the upper of 10 said fork bars having an opening alinable

with the opening in said container and the 15 lower of said bars having an opening alinable with the opening in said measuring chamber, a spring attached to the lower of 20 said fork bars adapted to hold them in a forward position, a handle permanently engaged with the bowl, a lever pivoted to said handle, said lever having a bent portion containing an eye, and operative connections between said fork bars and said eye.

In testimony whereof I have affixed my 25 signature.

PAUL EGNATOFF.
